A. J. JACKSON

MAGNETIC SHIPBUILDING DEVICE

Filed April 14, 1923

Archibald John Jackson Inventor

By Solon A. Polachek

Attorney

UNITED STATES PATENT OFFICE.

ARCHIBALD JOHN JACKSON, OF FORT OGDEN, FLORIDA.

MAGNETIC SHIPBUILDING DEVICE.

Application filed April 14, 1923. Serial No. 632,168.

To all whom it may concern:

Be it known that I, ARCHIBALD JOHN JACKSON, a subject of the King of Great Britain, residing at Fort Ogden, in the county of De Soto and State of Florida, have invented certain new and useful Improvements in Magnetic Shipbuilding Devices, of which the following is a specification.

10 This invention relates generally to ship construction, having particular reference to the securing of the hull plates on the ribs or framework, the invention having for an object the provision of magnetic means for 15 use in holding the plates in position on the ribs.

For further comprehension of the invention, and of the objects and advantages thereof, reference will be had to the following description and accompanying drawing, and to the appended claims in which the various novel features of the invention are more particularly set forth.

Fig. 1 of the drawing is a fragmentary side view of the hull of a ship, indicating the means whereby the plates are held on the frame according to my invention.

Fig. 2 is a side view of the magnetic plate holding device showing it engaged with one 30 of the ribs of the ship.

Fig. 3 is a plan view thereof, showing the rib in horizontal section.

Fig. 4 is a side view of the hull of a ship with parts broken away to show the ribs.

35 In the drawing I have indicated generally by the reference numeral 10 the steel plates of the hull of a ship, while 11 indicates the ribs of the ship to which such plates are secured. I preferably make use of magnetic 40 means in conjunction with the usual rivets for holding the plates to the ribs. This might be done by magnetizing the parts so that they would hold together without shaking or vibration.

45 I preferably utilize however, the novel device illustrated in detail in Figs. 2 and 3 and which comprises an elongated rectangular plate 14 of insulating material which serves as a base for the device.

50 Mounted on the forward side of this plate are several electro-magnets 15, as here shown four, arranged in pairs, one pair near each end of the plate, while the respective magnets of each pair are laterally spaced from one another to straddle the web of the T-

shaped rib 11. The device is adapted to be firmly clamped to the rib with the magnets 15 pressed against the cross element of the latter by pairs of gripper jaws in the general form of bell crank levers each having 60 a short arm 18 which forms the jaw proper, and a long arm 19 which forms the handle. These jaws are pivoted to the free ends of links 20 pivoted at their other ends to the base as at 21, and the respective jaws of each 65 pair are disposed on opposite sides of the web of the rib 11, the jaw arms 18 projecting toward one another from the links 20 and having sharpened ends which are adapted to bite the sides of said web. 70

To operate the jaws I provide a pair of solenoids 25 which are fixed one near each end of the base 14 and to the rear face thereof, with their axes transverse to the base. Pivoted connected to the outer ends of the 75 plungers 26 of these solenoids are pairs of rigid links 27 which are attached at one end to the said plungers, and at their opposite ends to the operating arms or handles 19 of the jaws. Surrounding the plunger 26 of 80 each solenoid is a coiled expansion spring 28 which urges the plunger outwardly, or in a direction to release the jaws. The base 14 may have a suspension eye 30 fixed to one 85 end thereof, whereby it may be attached to a chain or the like. Formed in the base toward opposite sides thereof, are the longitudinally extending slots 31 which permit of access to the heads of the rivets, indicated at 32, which are used to secure the plates 90 10 to the ribs 11. To adjust the device to grip webs of different thickness the free ends of the links 20 are held in variable position by means of tension springs 35 which urge them against abutment screws 36 threaded 95 through lugs 37 on the base 14.

As will be apparent, my improved arrangement facilitates the use of the rivets by the magnetic holding of the plates in position, and is of considerable convenience and 100 utility in shipbuilding.

Having thus described my invention what I claim as new and desire to protect by Letters Patent of the United States is as follows:

1. A plate holding means for the hulls of ships comprising magnets, a base on which said magnets are mounted, and gripper jaws on said base adapted to grip the ribs of the ship to hold the device in position thereon. 110

2. A device of the type described comprising a base, a pair of swinging gripper jaws mounted on said base and adapted to engage opposite sides of a part to be gripped, links hinged at one end to said base and carrying the said gripper jaws on their free ends and abutment members for the free ends of said links adjustable toward and away from one another, for the purpose specified.
3. A device of the type described comprising a base, a pair of gripper jaws, and adapted to engage opposite sides of a part to be gripped, and a solenoid for operating said jaws, links hinged to said base and having said jaws hingedly mounted in turn thereon, and means for adjusting said links toward and away from one another, for the purpose specified.
4. A device of the type described comprising a base, a pair of gripper jaws, and adapted to engage opposite sides of a part to be gripped, and a solenoid for operating said jaws, links hinged to said base and having said jaws hinged in turn thereto, and means for adjusting said links toward and away from one another, for the purpose specified, including springs pressing said links against abutment screws.

In testimony whereof I have affixed my signature.

ARCHIBALD JOHN JACKSON.
